UNITED STATES PATENT OFFICE.

ALEXANDER HOLLEY OLMS TED, OF HAVRE, FRANCE, ASSIGNOR TO WESTINGHOUSE ELECTRIC AND MANUFACTURING COMPANY, A CORPORATION OF PENNSYLVANIA.

POWER SYSTEM.

992,583.

Specification of Letters Patent. Patented May 16, 1911.

Application filed September 28, 1910. Serial No. 583,908.

To all whom it may concern:

Be it known that I, ALEXANDER HOLLEY OLMS TED, a citizen of the United States, and a resident of Havre, in the Republic of France, have invented a new and useful Improvement in Power Systems, of which the following is a specification.

This invention relates to the control of power systems of the kind or class now well known in which electric translating devices are operated from electric generators which are driven by internal combustion engines, and is particularly adapted for use in connection with electrically propelled vehicles forming a train comprising one or more self-propelled cars, each provided with one or more internal combustion engines, electric generators and electric motors driven thereby.

The object of the invention is to provide a system of this kind in which the control gear for both the electrical apparatus and the internal combustion engines of each self-propelled car can be operated from any desired point in the train. In order to attain this object, it is evidently necessary that two distinct operations shall be capable of being effected from the controlling point, namely, the simultaneous actuation of all the controllers for the electrical apparatus in each of the self-propelled vehicles of the train and also the simultaneous actuation of the controlling devices for each of the corresponding internal combustion engines. In propulsion systems of this kind the internal combustion engines are in operation throughout the whole time that the vehicles are in use, and according to the present invention I employ them as the source of power to move the controlling devices both for the engine itself and for the electrical apparatus of each car, suitable relay devices being provided to connect and disconnect the shaft of the engine from the operating shafts of the respective controlling devices in accordance with the adjustments effected by the driver on the car from which the control is being effected. The utilization of the engine as a source of power for operating the controlling devices also enables the carburetor of the engine to be very easily adjusted when necessary against the action of the centrifugal governor of the engine which would otherwise tend to keep the engine rotating at the normal maximum speed.

The invention is illustrated in the accompanying drawings of which—

Figure 1 is a diagrammatic view showing two self-propelled vehicles of a train provided with a control system embodying the invention. Fig. 2 is a similar view showing on a larger scale the mechanical details of one of the elements of the control system of Fig. 1. Fig. 3 is a diagrammatic view of a portion of the control system of Fig. 1 showing in simplified form, the controlling arrangements for the electrical apparatus of the system. Fig. 4 is a diagrammatic view of a part of the control system of Fig. 1 illustrating a modification in the controlling arrangements for the internal combustion engines. Fig. 5 is a detail view of a portion of the apparatus shown in Fig. 4.

Referring now to Fig. 1, two self-propelled vehicles forming a train are indicated diagrammatically at 1, 2, as provided with internal combustion engines indicated by rectangles at 3, 4 driving electric generators 5, 6, respectively. The internal combustion engines 3, 4 are provided with carburetors 7, 8 the controlling valves of which are operated by means of chains 9, 10 connected to chain wheels 11, 12 carried on the shafts 13, 14 of the clutch controllers 19, 20 respectively. 75 The armatures of the electric generators 5, 6 are mounted on the shafts 15, 16 of the engines 3, 4 these shafts also carrying the bevel gear wheels 17, 18 of the clutch controllers 19, 20 respectively. The chain 80 wheels 21, 22 of the clutch controllers are connected by chains 23, 24 to the shafts 25, 26 of the controllers 27, 28 for the electrical apparatus on the cars 1, 2 respectively. 85 Each of the controllers 27, 28 is provided 90 with a pilot drum 29, 30 mounted on the controller shaft.

Each car has a master controller 31, 32 and an electric traction motor 33, 34, the connections to the generators 5, 6 of the field magnet and armature windings of these motors being controlled in any suitable well-known manner by means of the controllers 27, 28. A set of train wires 35, extend along the train, and are connected to conductors 36, 37 connected between the contact fingers of the master controller 31, 32 and the contact fingers of the pilot drums 29, 30 respectively. The shafts 25, 26 are provided 100 with electro-magnetically released brakes 105 110

38, 39 for determining the positions of the controllers 27, 28 and the clutch controllers 19, 20 are provided with clutch electro-magnets 40, 41, 42, 43 and 44, 45, 46, 47 respectively. Each car is also provided with a differential relay device 48, 49 the electro-magnets 50, 51 and 52, 53 of which are connected in circuit with the power train wires 54, through switches 58, 59. Train wire 10, couplings 55, 56, 57 are also provided for coupling the train wires between adjacent vehicles. Batteries 60, 61 are carried on each of the self-propelled vehicles for supplying current to the various electro-magnets of the control system, and the circuit of each of the propelling motors 33, 34 is provided with an overload relay 62, 63.

The construction and operation of the clutch controllers 19, 20 for controlling the operation of the electrical and mechanical regulators of the system will be best understood from Fig. 2, in which the engine shaft is indicated at 15 as connected to the bevel gear wheel 17 of the clutch controller 19. 20 The gear wheel 17 engages with two gear wheels 114, 64 loosely mounted on the shaft 13 of the clutch controller and provided with friction cones 65, 66 and 67, 68 respectively. Intermediate the bevel gear wheels 114, 64 a bushing 69 is loosely mounted on the shaft 13, and provided with friction cones 70, 71 adapted to engage with the friction cones 66, 67 respectively. The bushing 69 also carries the chain wheel 21 for 25 operating the controller 27 (see Fig. 1) and is adapted to be moved into engagement with either the friction cone 66 or the friction cone 67 by means of a double crank lever 72, one arm of which is adapted to engage with flanges 73, 74 on the bushing 69, the other arms of the lever 72 being connected to the plungers of the electro-magnets 41, 42 respectively. Other bushings 75, 76 are also provided loosely mounted on the shaft 13 and having friction cones 77, 78, the bushings 75, 76 being connected to the shaft 13 by means of keys so that while rotating with the shaft 13, they are capable of longitudinal motion along the shaft so 30 as to bring the friction cones 77, 78 into engagement with the friction cones 65, 68 respectively. The engagement and disengagement of the friction cones 77, 65 is effected by means of pivoted lever 79 engaging with the bushing 75 and actuated by an electro-magnet 40, a similar lever 80 actuated by an electro-magnet 43 being provided for moving the bushing 76 so as to bring the friction cones 78, 68 into engagement with 35 one another.

The operation of the device is as follows:—The shaft 15 being continuously rotated by the engine will cause the gear wheels 114, 64 to rotate in opposite directions by means of the gear wheel 17. Assuming that

the electro-magnet 41 is energized, the bushing 69 will be moved toward the left by means of the lever 72 and the friction cones 66, 70 will engage with one another, thereby causing the bushing 69 with its attached 70 chain wheel 21 to be rotated in the same direction as the gear wheel 114. On the other hand, if the magnet 42 be energized the friction cones 71, 67, will be brought into engagement with one another and the bushing 69 will be rotated in an opposite direction, namely, the direction in which the gear wheel 64 is rotating. The chain wheel 21 can therefore be caused to rotate in one or the other direction according as 80 the electro-magnet 41 or 42 is energized. In a similar manner the chain wheel 11 which is mounted on the shaft 13 of the clutch controller, can be caused to rotate in one or the other direction according as the 85 electro-magnet 40 or 43 is energized, since if the former be energized, the friction cones 65 and 77 will be brought into engagement with one another and the shaft 13 will be rotated in the same direction as the gear 90 wheel 114, an opposite direction of rotation being obtained in the same manner when the electro-magnet 43 is energized. As indicated in Fig. 1, the chain wheel 21 operates the shaft 25 of the controller 27 for the electrical apparatus of the self-propelled vehicle, while the chain wheel 11 actuates the valve of the carburetor 7 of the internal combustion engine 3, so that the electro-magnets 40, 43 control the regulation of the 95 internal combustion engine and the electro-magnets 41, 42 control the regulation of the 100 electrical apparatus.

Referring now to Fig. 3, the arrangements for controlling the supply of current 105 to the magnets 41 or 42 of the clutch-controller in accordance with the position of the master-controller 31 will be described, Fig. 3 showing a simplified form of the 110 circuits involved. The master-controller as indicated is provided with contacts 115 mounted on an insulating drum in the usual manner, stationary contact fingers 81 being adapted to engage with the contacts 115. The pilot drum 29 of the controller 27 (not 115 shown in Fig. 3) is also provided with contacts 82, 83 arranged inversely to the contacts 80 of the master-controller 31, so that conducting portions on the master-controller 31 correspond to insulating portions on the pilot drum 29. Stationary contact fingers 84 adapted to engage with the contacts 82, 83 are provided connected to the contact fingers 81 by means of conductors 36 and additional contact fingers 85, 86 are provided connected respectively to one terminal of the electro-magnets 41, 42, the remaining terminals of these electro-magnets are connected together and through a battery 60 to a stationary contact finger 87 of the master- 120 125 130

controller 31. When the master-controller 31 is in its "off" position the fixed contacts assume the position indicated by the dotted lines $a-a$, and the controller can be moved from this position into others in which the fixed contacts assume the positions indicated by the dotted lines a, a, b, b , corresponding to the forward direction of rotation of the motors of the train, or by the lines a', a', b', b' , corresponding to the reverse direction of rotation of the motors. The pilot drum 29 is moved into corresponding positions in which the fixed contacts assume the various positions indicated by the dotted lines in the following manner:—Assuming that both the master-controller 31 and the pilot drum 29 are in the "off" position, and that the former be moved into the position a, a , a circuit will be completed from one pole of the battery 60 through the contact finger 87, contact 115 of the master-controller drum 31, through one of the conductors 36 to the corresponding contact finger 84, contact 88 of the pilot drum 29, contact finger 86, electro-magnet 41, back to the other terminal of the battery 60. The electro-magnet 41 being thus energized, the controller and its attached pilot-drum 29 will be moved through the medium of the clutch-controller in the forward direction as described with reference to Fig. 2 until the pilot drum 29 has reached the position a, a , whereupon the connection circuit just described will be broken at the contact 88. A similar action takes place if the master-controller 31 is moved on farther to its position b, b , the electro-magnet 41 remaining energized until the pilot drum 29 has reached its corresponding position. If the master controller drum 31 is moved in the reverse direction, toward the position b', b' a circuit will be completed in a similar manner from the battery 60 through the contact 82 and the electro-magnet 42, thus causing the controller and its attached pilot drum 29 to move in a reverse direction until it reaches a position corresponding to the position to which the master-controller has been set.

Referring now again to Fig. 1, the operation of the complete control system is as follows:—Both petrol engines 3 and 4 are started up in the usual way. The control of the electric and mechanical apparatus of the cars 1, 2 of a train being controlled by the driver of the car 1, the control of the internal combustion engine 3 on the car 1 may be effected manually by means of the handle 116, the electro-magnets 40 and 43 and the differential relay device 48 on the controlling car being inoperative. By means of the handle 116, the carbureter 7 is set into the desired position, and when it is desired to accelerate the motors, the master-controller 31 is moved from its off position into one of the running positions in the desired direc-

tion either forward or reverse. A circuit is thereby completed from the battery 60 on the car 1 through one or other of the electro-magnets 41, 42 as already described with reference to Fig. 3, thereby causing the chain wheel 21 and the controller shaft 23 gear'd therewith to rotate in the corresponding direction to move the controller 27 and its attached pilot drum 29 to a position corresponding to the position into which the master controller 31 has been adjusted. By means of the train wires 35 and the conductors 37, a circuit is simultaneously completed through the contacts of the pilot drum 30 on the car 2 and the corresponding electro-magnet 45 or 46 of the clutch-controller on this car which in a similar manner rotates the controller shaft 26 and moves the controller 28 and its attached pilot drum 30 into position corresponding to the position of the master-controller 31. The controllers 27, 28 being now in the desired running positions, the motors 33 and 34 are supplied with energy from the generators 5 and 6 respectively and the train proceeds at a corresponding speed.

The armature circuit of the generator 5 includes the electro-magnet 52 of the differential relay device 49 on the car 2, the switch 58 having been previously set in the position indicated. The armature circuit of the generator 6 on the other hand includes the electro-magnet 53 of the differential relay device 49, the switch 59 having been previously set in the position indicated, the circuit being completed by means of an end coupling 57. So long as the currents delivered by the generators 5 and 6 are equal, that is to say, so long as the engines 3 and 4 are running at the same speed, the differential relay device remains in the position shown in the figure. Should, however, the current delivered by the generator 5 exceed that delivered by the generator 6, the pull of the electro-magnet 52 will preponderate over that of the electro-magnet 53 and the relay arm 88 of the differential relay device 49 will engage with the contact 89, thereby completing a circuit from one terminal of the battery 61 through the contacts 88, 89, electro-magnet 47 of the clutch regulator 20 back to the other terminal of the battery 61. The electro-magnet 47 being thus energized will cause the shaft 14 to be rotated in a corresponding direction as already described with reference to Fig. 2, and the carbureter 8 will be correspondingly adjusted by means of the chain wheel 12 until the amount of current delivered by the generator 6 rises to a value equal to that delivered by the generator 5, whereupon the pull of the electro-magnets 52 and 53 of the differential relay 49 being once more balanced, the relay arm 88 will break the circuit of the electro-magnet 47 at the contact 89. A similar action

will occur if the current delivered by the generator 6 exceeds that delivered by the generator 5 in which case the relay arm 88 will be moved in the opposite direction to 5 complete a circuit through the electro-magnet 44 of the clutch regulator 20, and thereby cause the shaft 14 of the said regulator to adjust the carburetor 8, so as to effect an equalization of the loads on the engines 3 10 and 4. This action will of course take place if the car 2 is used as the controlling car, for the purpose of starting the engine 3.

The electro-magnetically released brakes indicated at 38, 39 on the controller shafts 15 are provided for the purpose of causing the controllers to assume definite positions and maintaining them in these positions. The actuating coil of the brake 38 is included in the circuits from the battery 60 which include the magnets 41 and 42 so that whenever one or other of these magnets is energized to cause the clutch regulator 19 to vary the position of the controller 29, the actuating coil of the brake 38 will also be 20 energized and release the brake and allow the controller 29 to be moved. As soon as the magnet 41 or 42 as the case may be is deenergized, which will occur when the controller has been moved to the desired position, the brake coil 38 will also be deenergized with the result that the brake will be applied and stop further movement of the controller. The coil of the brake 39 is included in circuit with the magnets 45, 46 and 25 this brake acts in a similar manner on the controller 30. In order to prevent too rapid acceleration of the traction motors 33, 34 when the master controller is moved from its "off" position to one or other of its running positions, the overload switches 62, 63 are provided. Switches used for this purpose are now well known and in the present case their actuating coils are included as usual in the motor circuit. The switches 40 are adapted to open the circuits described above in which are included the magnets 41, 42, 45, 46 and brake magnet coils 38, 39 so that further movement of the controllers 27 or 28 is prevented until the overload on 45 the motors 33 or 24 has subsided. In cases where the train comprises more than two self-propelled vehicles, it will be readily understood that all the electro-magnets corresponding to the electro-magnet 52 are connected in series with one another in the armature circuit of the generator on the car from which the control is being effected and the arrangements of the power train wires 50 54 must be modified accordingly.

55 Referring now to Figs. 4 and 5, an alternative arrangement for controlling the electro-magnets 44, 47 of the clutch controller 20 is illustrated, the shafts 15, 16 of the engines 3, 4 being provided with cams 90, 91 60 respectively adapted to engage with rollers

92, 93 carried on pivoted arms 94, 95. Upon the free ends of the arms 94, 95 bridging pieces 96, 97 are mounted, which are adapted to break contact with stationary pairs of contacts 98, 99 respectively, when the cams 90, 91 engage with their respective rollers 92, 93. The contacts 98, 99 are connected in the circuits of two electro-magnets 100, 101 respectively, which are energized from the battery 61, the said electro-magnets 100, 101 70 being arranged, as shown in Fig. 5, to operate pawls 102, 103 engaging with a pair of ratchet wheels 104, 105. The ratchet wheel 104 carries a contact 106 connected by means of a slip ring 107 to one terminal of the battery 61; the other ratchet wheel 105 carries a pair of contacts 108, 109 each of which is connected by means of a slip ring 110, 111 to one of the terminals of the electro-magnets 44, 47 of the clutch regulator 20 (see Fig. 1). The remaining terminals of the electro-magnets 44, 47 are connected to the other terminal of the battery 61 as shown in the figure. The operation of this form of the apparatus is as follows:—If the internal combustion engines 3 and 4 are rotating at the same speed, the bridge pieces 96, 97 will be intermittently disconnected from their respective contacts 98, 99 with the same frequency, thereby breaking 80 the circuits of the electro-magnets 100 and 101, and causing the pawls 102, 103 to rotate the ratchet wheels 104, and 105 at the same speed. The contact 106 will therefore remain in an intermediate position relative to the contacts 108 and 109 and the circuits of the electro-magnets 44 and 47 will be broken at these contacts. If, however, the speed of the engine 4 increases, the circuit of the electro-magnet 101 will be interrupted more frequently than that of the electro-magnet 100, so that the ratchet wheel 105 will be rotated at a greater speed than the ratchet wheel 104. The contact 108 will therefore come into engagement with the contact 106 and a circuit through the electro-magnet 47 will be completed, thereby operating the clutch regulator 20 to readjust the carburetor of the engine 4 as previously described with reference to Fig. 1. The converse action will take place if the speed of the engine 4 falls below that of the engine 3, in which case the circuit of the electro-magnet 101 will be broken less frequently than that of the electro-magnet 100 thereby causing the ratchet wheel 105 to be retarded relatively to the ratchet wheel 104, so that the contact 106 engages with the contact 109 and completes a circuit through the electro-magnet 44 of the clutch regulator. Instead of operating the carburetor of the internal combustion engine on the controlling car by means of the handle 116, shown in Fig. 1, a switch, 112, 113 on each of the motor vehicles may be 110 115 120 125 130

provided, these switches being provided with two fixed contacts connected respectively to the terminals of the electro-magnets 40 and 43 and a movable arm connected 5 to that terminal of the battery 60, to which the arm of the differential regulator 48 is connected. The switch 112 or 113 is operated by the motorman and serves to cause either the magnet 40 or the magnet 43 to be 10 energized, thus effecting adjustment of the carburetor of the controlling car in the manner already described. When this form of control is employed on trains comprising more than two self-propelled vehicles, it will 15 be readily understood that all the electro-magnets corresponding to the electro-magnet 100 must be connected in series or parallel with one another, a suitable arrangement of train wires being provided for this 20 purpose.

The arrangements herein described may evidently be considerably modified without departing from the spirit and scope of the invention.

25 What I claim is:—

1. An electrically propelled train comprising a plurality of vehicles, an engine on each vehicle, generators driven respectively by the engines, propelling motors for the 30 vehicles, respectively supplied from the generators upon the same vehicles as are propelled thereby, and means for controlling the operation of the engines and motors from a predetermined point on the train.

2. An electrically propelled train comprising a plurality of vehicles, an engine on each vehicle, generators driven respectively by the engines, propelling motors for the vehicles respectively supplied from the 40 generators upon the same vehicles as are propelled thereby, means for controlling the operation of the engines, and means for controlling the operation of the motors, said means comprising electrical connections between the vehicles.

3. An electrically propelled train comprising a plurality of vehicles, an engine on each vehicle, generators driven respectively by the engines, propelling motors for the 50 vehicles supplied from the generators, means for controlling the operation of the engines, and means for controlling the operation of the motors, said means comprising electrical connections between the vehicles.

4. In a power system, the combination with an internal combustion engine, an electric generator driven thereby and an electric motor supplied with current from said generator, of regulators actuated from the shaft 55 of the internal combustion engine for governing the operation of the engine and of the motor, and means for independently governing the actuation of the regulators.

5. In a power system, the combination

with an internal combustion engine, an electric generator driven thereby and an electric motor supplied with current from said generator, of regulators actuated from the shaft of the internal combustion engine for governing the operation of the engine and of the motor, and electrically operated means for independently governing the actuation of the regulators.

6. In a power system, the combination 75 with an internal combustion engine, an electric generator driven thereby and an electric motor supplied with current from said generator, of regulators for the internal combustion engine and for the electric motor, 80 a pair of clutch mechanisms for independently connecting the said regulators to the shaft of the internal combustion engine, and means for governing the engagement and disengagement of each clutch mechanism. 85

7. In a power system, the combination with an internal combustion engine, an electric generator driven thereby and an electric motor supplied with current from said generator, of regulators for the internal combustion engine and the electric motor, a pair of clutch mechanisms for independently connecting the said regulators to the shaft of the internal combustion engine, and electrical means for governing the engagement 90 and disengagement of each clutch mechanism. 95

8. In a power system, the combination with a plurality of engines, an electric generator driven by each of said engines, and 100 separate power circuits supplied respectively from the generators, of a regulator for each engine, means for adjusting the regulator of one of the engines, and means for automatically adjusting the regulators 105 of the remaining engines in accordance with the outputs of the corresponding electric generators relative to the output of the generator driven by the first engine.

9. In a power system, the combination of 110 two engines, an electric generator driven by each engine, separate power circuits supplied respectively from the generators, a regulator for each of said engines, clutch mechanism for actuating each of said regulators from the shaft of the corresponding engine, electromagnets for effecting the engagement and disengagement of the clutch mechanism, and a differential electromagnetic device for controlling the supply of 115 current to the circuits of the electromagnets, the opposing electromagnets of the differential device being connected in the circuits of the respective generators.

10. In a power system, the combination 120 of a plurality of internal combustion engines, an electric generator driven by each of said engines, a regulator for each engine, means for adjusting one regulator to control the speed of one of the engines, and 130

means dependent upon the relative speeds of the engines for automatically controlling the regulators for the remaining engines.

11. In a power system, the combination 5 of an internal combustion engine, an electric generator driven thereby, an electric motor supplied with current from said generator, a controller for the electric motor, a pilot drum mechanically connected thereto, means for operating the controller and pilot drum from the shaft of the internal combustion engine, electromagnets controlling said means, contacts mounted upon the

pilot drum, a master controller drum having contacts arranged inversely to those on 15 the pilot drum, and contact fingers and conductors connecting the pilot drum and the master controller drum.

In testimony whereof, I have hereunto subscribed my name this 9th day of September, 1910. 26
